(57) **CLAIM**

The ornamental design for a dust blower body as shown and described.

DESCRIPTION

FIG. 1 is a front, left, and top perspective view of a dust blower body in accordance with our new design;

FIG. 2 is a rear, right, and top perspective view of the dust blower body in accordance with our new design;

FIG. 3 is a front elevational view of the dust blower body in accordance with our new design;

FIG. 4 is a rear elevational view of the dust blower body in accordance with our new design;

FIG. 5 is a top plan view of the dust blower body in accordance with our new design;

FIG. 6 is a bottom plan view of the dust blower body in accordance with our new design;

FIG. 7 is a left side elevational view of the dust blower body in accordance with our new design;

FIG. 8 is a right side elevational view of the dust blower body in accordance with our new design; and,

FIG. 9 is a front, left, and top perspective view of the dust blower body in accordance with our new design illustrating a state in which environmental structures (a nozzle and a battery) is attached to the dust blower body.

The broken lines in the drawings illustrate the environmental structures or portions of the dust blower body which form no part of the claimed design.

1 Claim, 9 Drawing Sheets
